UNITED STATES PATENT OFFICE.

CHARLES H. HOFFSTETTER, OF ERIE, PENNSYLVANIA.

GAS HEATING-STOVE.

SPECIFICATION forming part of Letters Patent No. 634,498, dated October 10, 1899.

Application filed June 10, 1899. Serial No. 720,069. (No model.)

To all whom it may concern:

Be it known that I, CHARLES H. HOFFSTETTER, a citizen of the United States, residing at Erie, in the county of Erie and State of Pennsylvania, have invented certain new and useful Improvements in Gas Heating-Stoves; and I do declare that the following is a full, clear, and exact description of the invention, which will enable others skilled in the art to 10 which it appertains to make and use the same.

My invention relates to gas heating-stoves; and the invention consists in a stove constructed and having the features substantially as shown and described and particularly pointed out in the claims.

In the accompanying drawings, Figure 1 is a vertical central sectional elevation on a line corresponding to 1 1, Fig. 2. Fig. 2 is a vertical sectional elevation of the stove at right angles to Fig. 1 and on line 2 2, Fig. 1, except that the burner is shown in full lines and the supply-pipe is shown in section. Fig. 3 is a horizontal section of the top of the stove looking down on line 3 3, Fig. 2. Fig. 25 4 is a horizontal section looking down on line 4 4, Fig. 2.

The stove thus shown is designed more particularly for burning natural gas, in the use of which good health demands that the products of combustion should be carried off directly from the stove to the chimney, so as to avoid their diffusion in the atmosphere of the room and the consequent corruption of the air and its inevitable consequences upon the 35 health of the occupants.

Heretofore as a very general thing the appliances for utilizing natural gas for domestic heating have been exceedingly crude, and however much they varied in character they all 40 most invariably were without any provision for ventilation or carrying away the deleterious gases that unavoidably attend the use of burners, either by reason of imperfect combustion or from the products of combustion 45 themselves. Some efforts have been from time to time made to remedy this acknowledged objection; but so far as I am aware the best or most satisfactory results have not been attained by any of them. I have sought, 50 therefore, to construct a stove for this special

use which has two distinct advantages in view—viz., the maximum elimination of the heat generated, so that there shall be no waste on this account, and the separation of combustion and its products from the atmosphere which passes into the room and the discharge of said products into the flue and chimney provided to carry them away.

To these several ends I have constructed a stove substantially as shown, wherein utility 60 is combined with symmetry and attractiveness in design or style. In this construction A represents the base of the stove, and B the body, in which is the heating-chamber proper, having the burner C openly exposed therein 65 at its bottom. The bottom of the stove is perforated or has openings for the entrance of air to supply the burner within the chamber, and on the top of said chamber and body B is the radiating and reflecting plate or part 70 D, which rests at its ends and front on the walls of the body B and at its rear on the inner wall E of the combustion and heating chamber. This plate D is constructed with flues 2 at its ends, and these flues extend up 75 flush with the top plate proper, F, of the body of the stove, and the said parts are constructed to make a close union and to avoid leakage, the top F having openings to match the flues 2. This construction leaves the body of plate 80 D on a plane sufficiently below the top F to form an air-space between them, and air is admitted to this space and thence upward into the radiating and conveying flues G and H through the ample passage 3 at the rear of 85 the burner-chamber, between walls B and E and at the front through the entrance 4 beneath the overhanging front of the top plate F, the air-space as to plate D being between its two end flues 2.

The plate or top F of the body of the stove has flanged holes to accommodate the hot-air flues G and H and the combustion or draft flues K, which are arranged over the draft flues or passages 2. Flues G and G are of 95 the same size as here shown, while flue H, intermediate of these, is of considerably larger capacity, and all the said flues are of the same length and surmounted by a plate L common to all of them and having an open- 100

ing for each to continue its passage thence onward, the hot or heated air for the room issuing into the room at the top through the open-work crown-plate M, while the products of combustion pass on to the outlet 6 and to the chimney, Fig. 1. Complication of the flues and intermixture of their contents in the extreme top of the stove, where all the pipes or flues G, H, and K discharge, is prevented by a division-wall N, which at its ends is shown in plan, Fig. 3, as splitting the openings 7 in plate L and skirting at its rear and longer portion the rear of air-openings 8 and 9 from flues G and H, so as to provide a draft-passage across the rear and top of the said top for the products of combustion to the outlet 6.

By referring to Fig. 2 it will be seen that plate L is built out at 1 to cover half the space occupied by the pipes K, which, however, leaves ample room for the exit of the products of combustion and by choking the same back at this point promotes radiation of heat therefrom. A somewhat corresponding contraction of the draft-passage occurs at the bottom of draft-pipes K for a like purpose, so that as a result of the construction as a whole I am enabled to extract practically all the heat obtained from the burner and without occasion to inhale any of the odor or poisonous gases arising therefrom. Neither is there any danger of explosion from accidental flow of gas with a stove of this kind, because there is draft enough to carry the gas off as fast as it flows.

Among the features of importance and novelty in this stove I mention—

First. The back flue or passage open at the bottom and extending upward and directly over the fire-chamber, covering the entire top of the fire-chamber and forming a back wall for the said fire-chamber. This back flue extends clear over the top of the fire-chamber, forming a sort of roof, and is again opened at the front of the heater directly over the door, thereby taking in a draft of air from the front of the stove as well as the back.

Second. The method of conducting the waste products from the fire-chamber upward through the end flue-pipes and out into the chamber on top of the flue-pipes, and thence out through the pipe-collar and into the chimney. The flue in the top of this register or chamber or radiator I consider one of the most valuable points in the stove, inasmuch as it leaves the entire top surface open for the heat to radiate out into the room, and the waste products, which come directly from the fire-box or chamber, are carried off through a flue which is at the rear.

Third. All the waste products from the burned gas pass around through the end flues constructed for their use and directly up into the chimney, allowing none of these odors to pass into the room, thereby making all of the

heat which is deposited in the room pure air, which is taken from the room, passes through the stove in the various flues constructed for this purpose, but passes upward and out through the radiator on the top of the flue-pipes into the room, altogether as pure when it returns to the room as when it entered the heater.

The "draft-flues" herein referred to mean the combustion-flues, in contradistinction to the fresh-air flues, while the "air" flues or passages have reference to the heated air for the room.

What I claim as new, and desire to secure by Letters Patent, is—

1. The body of the stove, a top plate thereon and a heat-radiating plate beneath said top plate, said plates constructed to form a hot-air chamber between them, draft-flues from the combustion-chamber through said plates exterior to the said hot-air chamber, and pipes in communication with said flues and said chamber, substantially as described.

2. The stove-body and the two plates on its top spaced apart to form a hot-air chamber between them, and having walled draft-flues at its sides outside said chamber, and a fresh-air passage across its rear from bottom to top leading into said chamber, substantially as described.

3. The body of the stove having a top with two horizontal plates, the lower plate provided with a draft-flue at each end and narrower than the top plate to afford an air-passage upward at its rear, said body having a fresh-air passage the full width across its rear and a like passage at its front between said two plates, and draft and fresh-air pipes, respectively, surmounting said top, substantially as described.

4. The body of the stove comprising a combustion-chamber provided with side flues at its top and an air-heating chamber with a flue or flues between said side flues, a walled fresh-air passage across the rear of the stove and two horizontal plates at its top, the upper of said plates provided with openings to receive draft and hot-air pipes, respectively, and the lower plate constructed to divide the draft and air passages to said pipes, the pipes set in said openings and a top surmounting said pipes, substantially as described.

5. The stove comprising a combustion-chamber provided with side flues and an air-heating chamber having flues between said side flues, pipes connecting with said flues and a top constructed of three several parts consisting of a plate with holes resting on said pipes, an interior wall around the hot-air flues and an exterior top plate resting on said wall and said lower plate and constructed to afford a passage from the draft-flues at the sides of the stove to the single outlet at its rear, substantially as described.

6. The body of the stove having a combus-

tion-chamber within the same and draft-flues therefrom at its sides, an air-heating chamber across the top of the stove between said draft-flues, a fresh-air-supply passage leading into said air-heating chamber and suitable outlet-openings for the hot air, substantially as described.

Witness my hand to the foregoing specification this 3d day of June, 1899.

CHARLES H. HOFFSTETTER.
